UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DOUBLE SHUTTLE MOTION.

Application filed January 2, 1924. Serial No. 683,885.

To all whom it may concern:

Be it known that I, WILLIAM M. WATTIE, a citizen of Canada, residing at Worcester, in the county of Worcester and State of 5 Massachusetts, have invented a new and useful Double Shuttle Motion, of which the following is a specification.

This invention relates to improvements in positive shuttle motions for double pile 10 fabric looms and more particularly to means for reinforcing the shuttle operating rods in the type of loom shown in Patent No. 1,268,098 issued June 4, 1918.

The loom set forth in that patent is provided on each side thereof with a pair of shuttle supporting rods which are carried by a sliding block and provided with latches to cooperate with tongues formed on the ends of the shuttles. As generally used one 20 shuttle is on the upper rod of the pair on one side of the loom and the other shuttle on the lower rod on the opposite side of the loom and the pairs of rods are moved together so that each shuttle may be transferred from one pair of rods to the other, after which they are separated and the shuttles carried entirely through the shed. In 25 looms weaving coarse fabrics such as cocoa mats the shuttles are very heavy and it has been found that the rods are likely to sag so that the shuttle will strike the lower 30 plane of the shed over which it is to pass.

The principal object of my invention is to provide means for bracing the members 35 of each pair of rods so that one will brace the other; the result being that the weight of the shuttle is supported by two rods instead of one as in the construction illustrated in the aforesaid patent.

40 A further object of my invention is to provide adjustable means for bracing the rods by which the said rods may be spaced so as to permit the weaving of fabrics of varying heights of pile.

45 A still further object of the invention is to provide means to tie the shuttle rods together so arranged that the point of connection between the rods will be the same distance from the shuttle irrespective of the 50 longitudinal adjustment of said rods in their blocks.

With these and other objects in view which will appear as the description pro-

ceeds, my invention resides in the combination and arrangement of parts hereinafter 55 described and set forth in the claims.

In the accompanying drawings, wherein a convenient form of my invention is shown,

Fig. 1 is a front elevation of a portion 60 of a loom showing my invention applied thereto,

Fig. 2 is an enlarged detailed front elevation of the right hand pair of shuttle holders and their driving block,

Fig. 3 is a top plan view of the structure 65 shown in Fig. 2, and

Fig. 4 is an enlarged section taken on line 4—4 of Fig. 2.

Referring more particularly to Fig. 1 it will be seen that the loom sides 10 have secured thereto side frames 11 to which are pivotally connected levers 12. A gear 13 mounted on the loom frame rotates with the shaft 14 which may be driven in any approved manner. Pinion 15 is fastened to 70 shaft 16 to cause the latter to make one complete rotation when the teeth 17 on the gear 13 engage and rotate the pinion 15. Fastened to the shaft 16 are oppositely extending arms 18 which are connected to the 75 levers 12 by means of adjustable links 19. Each frame 11 is provided with a guideway 20 on which slides a block 21 which receives motion from lever 12 by means of link 22 and stud 23 rigid with the block 21. The 80 matter thus far described is substantially as set forth in the aforesaid patent and forms no part of my invention.

My invention relates more particularly to 85 the rods and operating blocks for the shuttles, and as the mechanism on each side of the loom is the same, I will describe the motion on one side only. Each block 21 comprises a plate 24 formed with a dove-tailed extension 25 which is received by the guideway 20 and has secured thereto the stud 23. Associated with the plate 24 is a pair of block members 26 and 27, which are formed to receive the rounded portions of rods 28 and 29, respectively. (See Fig. 4.) In 90 order to secure the rods in place each member is provided with an opening 30 which receives the head 31 of a screw 32 which passes through a collar 33 and is held there-to by nut 34. The head 31 and collar 33 lie 95 on opposite sides of the adjacent rod and as

the screw is tightened these two parts of the fastening means are clamped against the rod to hold the same in place. By this construction it is possible to adjust the rods longitudinally of the block.

In order to fasten the members to the plate 24 I provide the lower member with an upstanding extension 35 and the upper member with a depending extension 36, each of these extensions being provided with slots 37 through which passes a bolt 38 the head of which is seated in plate 24. By means of nut 39 on the screw 38 the members 26 and 27 are securely fastened to the plate 24 and by reason of the slots 37 it is possible to vary the distance between the rods 28 and 29. Screw 40 is threaded in the upper member 27 and is placed to engage the extension 35, thereby permitting close adjustment of the rods. Slots 41 formed in the plate 24 receive ribs 41' formed on the block members to hold them against angular motion.

Referring particularly to Figs. 2 and 3 it will be seen that each rod is provided with a socket 42 having formed therein a slot 43 so proportioned as to receive the tongues 44 of the shuttles. Pivoted to each rod is a lever 45 having a hook 46 which extends into the socket and across the slot 43 and is held yieldingly in such position by spring 47 secured to the rod. A controller arm 48 is pivotally mounted to each rod and has a cam portion 49 which is positioned to engage tripping devices (not shown) to release the shuttle at the proper time. The rods, sockets, and hooked and releasing levers are substantially the same as shown in the aforesaid patent and may be operated as indicated therein.

An important feature of my invention is the means by which the inner ends of the rods are coupled together so as to form mutual supports for each other to more efficiently support the shuttles. To accomplish this result I have provided a bolt 50 which extends between the rods and is threaded therein as closely to the sockets 42 as the selvage of the cloth will permit. The bolt is held in place by nuts 51 and may be adjusted so that the outer ends of the rods are the same distance apart as the ends received by the block 21.

The operation of the loom is the same as set forth in Patent #1,268,098, the upper shuttle being on one side of the loom and the lower shuttle on the opposite side. As the blocks 21 move inwardly the advancing tongues of the shuttles enter the approaching socket of the opposite rod and by means of the cam faces on the releasing levers the shuttle is released from the rod which moved it to mid-position and is connected to the opposite rod which operates to finish the motion of the shuttle through the shed. It will be seen by the arrangement set forth

that the bolts 50 tie the rods of each pair together so that the shuttles are given additional support and are presented to their respective sheds without objectionable sagging. This result is attained without interfering with the locking and releasing levers. The rods are mounted for endwise adjustment relative to the blocks 21 to accommodate various widths of fabrics and lengths of shuttles, but it will be seen that with such variations the rods 50 and the levers carried thereby will always be the same distance from the shuttle irrespective of the distance between the shuttle and the blocks 21.

Having thus described my invention it will be evident that changes and modifications may be made therein by those skilled in the art without departing from the spirit and scope of the invention as set forth in the claims and I do not wish to be otherwise limited to the details herein disclosed, but what I claim is:

1. In a double shuttle motion for looms, a pair of shuttle supporting rods, shuttle receiving and releasing devices on each of said rods, means to move said rods together toward and from weaving position, a shuttle supported on one of said rods, and means passing from one of said rods to the other of said rods to cause both rods to support said shuttle.

2. In a double shuttle motion for looms, a reciprocating block, a pair of rods carried thereby, shuttle receiving and releasing devices on each of said rods, a shuttle attached to one only of said devices, and means spaced from said block to connect the ends of the rods adjacent the shuttle whereby each rod assists in supporting said shuttle.

3. In a double shuttle motion for looms, a reciprocating block, a pair of rods longitudinally adjustable in said block, shuttle receiving and releasing means on each of said rods, a shuttle carried by one only of said rods, and means adjacent the shuttle to connect said rods together to cause each rod to support the shuttle.

4. In a double shuttle motion for looms, a block reciprocatingly mounted on the loom, rods carried by said block adjustable in the direction in which the block slides and also transversely of said direction, shuttle receiving and releasing means on each rod, a shuttle received by one only of said receiving and releasing means, and means connecting the ends of the rods together to cause both rods to support the shuttle and permit adjustment of said rods transversely of the direction in which said block moves.

5. In a double shuttle motion for looms, a reciprocating block, a pair of spaced rods carried thereby, shuttle receiving and releasing means carried by each rod, a shuttle carried by but one of said receiving and releasing means, and a connector extending

between the ends of the rods adjacent the shuttle to tie said rods together and cause each to assist in supporting the weight of the shuttle.

- 5 6. In a double shuttle motion for looms, a reciprocating block, a pair of rods carried by said block, shuttle receiving and releasing means carried by each rod, a shuttle carried by but one of said receiving and releasing 10 means, and connections between the ends of the rods adjacent the shuttle to connect said rods together and to cause each to assist in supporting said shuttle, portions of the re-

ceiving and releasing means being located between the block and said connections. 15

7. In a double shuttle loom, a shuttle motion on each side of the loom comprising a pair of spaced rods, a shuttle attached to each pair of rods and connections between the rods of each pair to transfer part of the 20 weight of the shuttle from the shuttle supporting rod of one pair to the other rod of the same pair.

In testimony whereof I have hereunto affixed my signature.

WILLIAM M. WATTIE.
